CLAIM

The ornamental design for a clothing accessory, as shown and described.

DESCRIPTION

FIG. 1 is a front elevational view of a clothing accessory showing my new design;

FIG. 2 is a side elevational view thereof;

FIG. 3 is a perspective view showing the clothing accessory in use;

FIG. 4 is a top plan view thereof; and,

FIG. 5 is a bottom plan view thereof.

The broken line, showing portions of the human form in FIG. 3, forms no part of the claimed design.
